[57] CLAIM

The ornamental design for an arm for adjustable sand chair, as shown and described.

DESCRIPTION

FIG. 1 is a bottom perspective view of an arm for adjustable sand chair embodying my new design;

FIG. 2 is a front end elevational view thereof;

FIG. 3 is a rear end elevational view thereof;

FIG. 4 is a side elevational view of the side exposed in FIG. 1;

FIG. 5 is a side elevational view of the side opposite to that shown in FIG. 4;

FIG. 6 is a top plan view thereof;

FIG. 7 is a bottom plan view thereof; and,

FIG. 8 is a top perspective view of a modified form of my new design in arm for adjustable sand chair.
